UNITED STATES PATENT OFFICE.

GEORGE KREMENTZ, OF NEWARK, NEW JERSEY.

DESIGN FOR A FINGER-RING.

SPECIFICATION forming part of Design No. 12,339, dated July 5, 1881.

Application filed May 21, 1881. Term of patent 7 years.

To all whom it may concern:

Be it known that I, GEORGE KREMENTZ, of Newark, Essex county, New Jersey, have invented a new and original Design for Finger-
5 Rings, of which the following is a specifica-
tion.

In the accompanying photographic illustration a perspective view of my newly-designed finger-ring is shown.

10 My new design relates to that class of finger-rings known as the "Marquis" ring, and in which the outer surface of the shanks and the head form one continuous curve.

15 The ends of the shanks A are provided with a leaf ornament, B, composed of two outwardly-curved end leaves with curved smooth outer edges, and of serrated inner edges, and of one or

more straight intermediate leaves with partly smooth and partly serrated edges. The openings between the leaves extend through the 20 entire thickness of the shanks.

Having thus described my invention, I claim as new and desire to secure by Letters Patent—

The herein-described design for finger-rings, 25 consisting of a leaf ornament at the ends of the shanks, and composed of two curved end leaves with smooth outer and serrated inner edges, and of an intermediate leaf with partly smooth and partly serrated edges, as set forth. 30

GEORGE KREMENTZ.
